(57) **CLAIM**

The ornamental design for a reed diffuser, as shown and described.

DESCRIPTION

FIG. 1 is a perspective view of a reed diffuser, illustrating our new design;

FIG. 2 is a front elevational view of the reed diffuser of FIG. 1;

FIG. 3 is a rear elevational view of the reed diffuser of FIG. 1;

FIG. 4 is a left elevational view of the reed diffuser of FIG. 1;

FIG. 5 is a right elevational view of the reed diffuser of FIG. 1; and,

FIG. 6 is a top plan view of the reed diffuser of FIG. 1. Unshaded portions of the drawing figures enclosed within broken lines form no part of the claim, and structures illustrated in broken lines without shading are environmental structures that also form no part of the claim. Additionally, the color of the vessel forms no part of the claim.
